(57) **CLAIM**

The ornamental design for a multi-functional food preparation platform, as shown and described.

DESCRIPTION

FIG. 1 is a perspective view of a multi-functional food preparation platform.

FIG. 2 is a top plan view of the multi-functional food preparation platform of FIG. 1.

FIG. 3 is bottom plan view of the multi-functional food preparation platform of FIG. 1.

FIG. 4 is a side elevational view of the multi-functional food preparation platform of FIG. 1.

FIG. 5 is another side elevational view of the multi-functional food preparation platform of FIG. 1.

FIG. 6 is another side elevational view of the multi-functional food preparation platform of FIG. 1; and,

FIG. 7 is another side elevational view of the multi-functional food preparation platform of FIG. 1.

The broken lines in the drawings are for illustrative purposes only and form no part of the claimed design.
